UNITED STATES PATENT OFFICE.

GODFREY M. S. TAIT, OF MONTCLAIR, NEW JERSEY, ASSIGNOR TO TAIT PRODUCER COMPANY, OF NEW YORK, N. Y., A CORPORATION OF NEW JERSEY.

GAS-PRODUCER.

1,165,347.

Specification of Letters Patent.

Patented Dec. 21, 1915.

Application filed March 4, 1910. Serial No. 547,194.

To all whom it may concern:

Be it known that I, GODFREY M. S. TAIT, a subject of the King of England, and a resident of Montclair, in the county of Essex 5 and State of New Jersey, have invented certain new and useful Improvements in Gas-Producers, of which the following is a full, clear, and exact specification, such as will enable others skilled in the art to which 10 it appertains to make and use the same.

My invention relates to the construction and organization of the producer at the grate thereof, whereby I am enabled effectually to hold up the fuel mass yet allowing 15 a maximum of air surface uniformly distributed over the whole area of the grate insuring a uniform fire.

A further feature of the invention is the arrangement by which I am enabled to discharge the ash in an extremely convenient 20 and simple manner without constructing the grate with moving parts adapted to be agitated in the manner of grates heretofore constructed.

Still a further feature of my invention resides in the manner of connecting the grate in the walls of the producer, according to 25 which I utilize as the grate frame the supporting plate of the fire brick with which 30 the producer is lined and combine the parts in a peculiar manner especially adapting 35 them to conditions common in gas producer work. And a further feature resides in the provision of hollow grate bars of peculiar 40 form adapted to the other features of my improvement and by means of which water may be circulated through the bars to cool 45 them and to provide a vaporizer generating vapor for use as an endothermic agent in the draft current.

My invention involves various other features of importance, all of which will be fully set forth hereinafter and particularly pointed out in the claims.

Reference is now had to the accompanying drawings, which illustrate, as an example, the preferred form of the invention.

In said drawings: Figure 1 represents a front elevation of the lower part of the producer equipped with my invention; Fig. 2 is a cross-section of the lower portion thereof, showing in part the ashes as they lie on the grate. Fig. 3 is a plan view of the grate and fire-brick ring; Fig. 4 is an enlarged

cross-section of the grate and ring; Fig. 5 55 is an enlarged section in a direction longitudinal of the grate bars; Fig. 5^a is a detail of the view of one of the grate bars; Fig. 6 is an enlarged plan of the lower section of the grate; Fig. 7 is a sectional elevation showing a modification adapted to 60 grates of large area; Fig. 8 is a sectional elevation showing the grate bars hollow for water circulation; and Fig. 9 is a section on the line 9—9 of Fig. 8.

10 indicates the metal shell of the producer; 11 its fire brick lining; 12 the metal supporting ring of such lining and 10^a the downward extension of the metal shell forming the inclosing walls of the ash pit. 65

As shown in Figs. 1 and 2 the ash pit walls are provided with a draft current opening 14 and an ash door 15. The walls 10^a at the top of the ash chamber are also formed with openings 16 in the front and 70 back through which the poke bars are introduced to rake the ashes from the grate as will fully appear hereinafter. 17 indicates 75 doors by which these openings are closed.

As shown best in Fig. 3 the brick-ring 12 80 is made in sections of which there are preferably four, said sections being provided at their ends with flanges 12^a bolted together to form a continuous ring. The sections are further provided with hook-lugs 18 extending 85 inward from the ring and adapted to enter notches 19 in the ends of the grate bars 20, said grate bars are angle-shaped and are disposed with their sloping sides upward, the bars being open at their lower 90 sides. The bars have cross-end walls 19^a in which the said notches are formed. In this manner the bars are supported on the brick-ring and are held spaced from each other 95 so that the ash may fall between them. The bars 20 are preferably ribbed on their undersides, as indicated at 20^a, and to prevent sagging at their middles a trussed-supporting beam 21 is provided. This beam extends under the grate bars diametrically across the producer and is adjustably hung at its ends by bolts 22. The beam 100 engages the under edges of the grate bars and is joined thereto by lugs and bolts 23.

As indicated at Figs. 3 and 4 the two end 105 grate bars at the ends of the beam 21 are formed curved corresponding to the curvature of the producer walls, and instead of

being of a cross-sectional form in the shape of an equilateral triangle, are formed with one side sloping in toward the center and the outer side vertical. As illustrated best in Fig. 3 the grate bars are formed with openings 24 in their ridges to increase the air surface of the grate. As shown best in Fig. 4, below the grate bars 20, are a number of bars 25 which have flat or plane upper surfaces excepting the two on the extreme ends. These grate bars 25 are preferably ribbed on their undersides as indicated at 26 and they are disposed so that they lie respectively under the spaces between the upper grate bars 20. As shown in Fig. 2, the lower bars 25 are also respectively opposite the openings 16. By this arrangement the ash falls between the upper grate bars 20 upon and sustained by the lower grate bars 25 at the angle of repose of the ash in the manner illustrated in Fig. 2. This, it will be seen, effectually sustains the ash and consequently the fuel bed allowing, however, a maximum opening for the flow of the draft current. To cause the ash to fall it is only necessary to introduce poke bars through the openings 16, sweeping such bars over the plane surfaces of the lower grate bars 25, thus disturbing the ash lying in the angle of repose and causing it to fall through the spaces between the bars 25 into the ash pit and allowing the ash above to take the place of the ash thus thrown down. The bars 25 at the extreme sides have their outer edges turned up to form lips 27 which prevent the ash from falling at this point and cause the ash to fall inward over the inner edge of said extreme bars 25. For the purpose of easy introduction of the brace beam 21 said lips 27 are recessed at their middle as indicated at 27^a in Figs. 4 and 6.

As shown best in Fig. 6 the flat lower bars 25 have their ends widened as at 25^a, so that at such ends the lower bars substantially touch each other. On their under surfaces the bars are provided with transverse strengthening ribs 28 and at the widening ends of the bars with ribs 28^a extending to bosses 29 formed on the undersides of the grate bars and matching with each other to form cavities 30 receiving the bolts 31, by which the lower bars are supported. Said bolts 31 depend from sockets 32 formed in the brick-ring 12 and by adjusting the nuts 33 of such bolts the height of the lower grate bars may be adjusted. In this manner I am enabled to adapt the grate readily to different conditions of fuel and operation, insuring that the parts are so disposed that they will operate properly to sustain the ash. The gas producer thus arranged provides a most effective grate which may be easily assembled and readily taken down in part or in whole for repair and adjustment. It

provides a wide and uniform area of air passage, insuring uniform combustion of the fuel, and it further provides for uniform shaking of the ash throughout the whole area of the fire. In grates of large area the length of the bars is so great that there is danger of sagging and to overcome this I employ the structure shown in Fig. 7. There both sets of grate bars are divided diametrically across the producer and their inner ends are supported by an I-beam 34 in turn sustained by legs 35 rising from the floor of the ash pit. On the top of the beam 34 are lugs 36 carrying pins 37 which fit in orifices in the inner ends of the upper series of bars. Said bars are supported by the beam and properly spaced by the pins 37. The lower tier of bars rest on the lower flange of the I-beam 34. At their outer ends the bars are supported and constructed as before described.

Figs. 8 and 9 show the water cooled form of the invention. Here the grate is also divided at its center and 38 indicates the supporting beam which corresponds with the beam 34 in Fig. 7. In Figs. 8 and 9 the lower bars 25 are constructed as in Fig. 7 and supported on the lower flange of the beam 38. Above the upper flange of the beam 38 it is provided with walls, preferably integral with the beam, forming two ducts 39 and 40 extending longitudinally through the beam from end to end thereof. At one end of the beam, as shown in Fig. 8, the beam is dropped and extended under the ring to a point adjacent the shell 10 forming extension ducts 39^a and 40^a with which water supply and return pipes may be connected. The upper duct 39, is the supply and the lower duct, 40, the return or overflow. The upper grate bars 41 are hollow and with the cross-section of an equilateral triangle. They rest on the upper flange of the beam 38 and are held spaced from each other by lugs 44 cast or otherwise formed on the sides of the walls forming the ducts 39 and 40. In the inner ends of each hollow bar 41 two nipples 42 and 43 enter. The nipples 42 are threaded into the wall of the duct 39 and fit loosely in openings in the grate bars, while the nipples 42 as threaded in the ends of the grate bars and fit loosely in openings in the upper part of the wall of the duct 40. By this arrangement the water enters the grate bars through the pipes 42 and is maintained at the level of the pipes 43. When that level is exceeded the water overflows through the pipes 43. In the bottoms of the hollow bars 41 are vertical tubes 45 which are open throughout and extend through the bottoms of the bars. The upper ends of the tubes are open to allow the vapor and steam generated to escape. In assembling the grate shown in Figs. 8 and 9, the hollow bars are tilted slightly so that the tubes

42 and 43 may be entered in the orifices as described and then the outer ends of the bars are dropped on their supports, which have been before described.

5 The construction is of much advantage in down draft producers, since it allows of cooling the grate and preventing their destruction by the intense heat evolved. It is also of much importance in serving as a vaporizer to supply steam, particularly in an up draft producer where the steam may pass directly into the fire with the draft current through the grate.

Having thus described my invention, what 15 I claim as new and desire to secure by Letters Patent of the United States, is:

1. A gas producer having a grate frame, a series of grate bars arranged side by side and spaced from each other, means for 20 mounting said bars on said frame, a second series of grate bars arranged below the first series and respectively under the spaces between the bars of said first series and having ash supporting top surfaces of a greater 25 breadth than said spaces, whereby the ash falling through the spaces between the bars of the first series lies in angle of repose hillocks upon the bars of the second series, said bars of the second series formed for lateral 30 discharge of the ash, and means for mounting the bars of said second series on the said 35 grate frame.

2. A gas producer having an encircling grate frame, a series of grate bars arranged 40 alongside of each other and spaced apart, means for mounting the grate bars on the frame, a second series of grate bars arranged below the first and having flat upper surfaces, the second series of bars being respectively 45 below the spaces between the bars of the first series, whereby the ash falls through said spaces and rests upon the flat surfaces of the second series of grate bars at the angle of repose and means for mounting the second series of grate bars on the grate frame.

3. A gas producer having a grate frame, a series of grate bars arranged side by side and spaced from each other, means for 50 mounting them on the frame, a second series of grate bars arranged below the first and opposite the said spaces between them, whereby the ashes fall through the said spaces and lie on the second series of grate 55 bars at the angle of repose and means for adjustably mounting the second series of grate bars so that they may be moved toward and from the first, for the purpose specified.

4. A gas producer having a grate frame, 60 a series of grate bars arranged side by side and spaced from each other, a second series of grate bars arranged below the first series and respectively under the spaces between the bars of the said first series and having 65 ash supporting top surfaces of a greater

breadth than said spaces, whereby the ash falling through the spaces between the bars of the first series lies in angle of repose hillocks upon the bars of the second series, and means for adjusting the position of one of said series of grate bars with respect to the other series.

5. A gas producer having a grate frame, a series of grate bars arranged alongside of each other and spaced apart, the upper surfaces of said bars slanting from the middle, a second series of grate bars arranged below the first and having flat upper surfaces opposite the spaces between the first series of grate bars, whereby the ash falls between the first series and rests on the second series at the angle of repose and means for mounting the grate bars in the frame.

6. A gas producer having a grate frame, a series of grate bars arranged side by side and spaced from each other, a second series of grate bars arranged below the first series and respectively under the spaces between the bars of said first series and having ash supporting surfaces, whereby the ash falling 85 between the spaces of the bars of the first series lies in angle of repose hillocks upon the bars of the second series, and means for mounting said series of bars on the grate frame, the producer wall having openings 90 therein at approximately the level of the lower series of bars and adapted to admit introduction of an instrument for throwing down the ash resting upon the bars of the lower series.

7. A gas producer having two series of grate bars, one above the other, the bars of each series being spaced from each other, and the bars of the lower series being located beneath the spaces between the bars of the upper series, and having ash supporting top surfaces, the producer having in its wall an opening at approximately the level of the lower series of bars, through which opening 105 an instrument may be introduced for throwing down the ash resting upon the bars of the lower series.

8. A gas producer having a frame a grate frame, an upper series of grate bars inclosed thereby, the grate frame having parts on which the ends of the upper series of bars are engaged to support said bars, a lower series of grate bars in staggered relation to the upper bars, means for suspending the lower series from said grate frame, a supporting beam extending under the upper series of bars intermediate their ends and means for suspending the supporting beam from the grate frame.

9. A gas producer having two series of 115 grate bars one above the other in staggered relation, the lower series of bars being widened at their ends to contact with each other and suspending means for the lower series, such means passing between the meeting 120 125 130

- edges of the ends of the grate bars and bearing under such bars to sustain them.
10. A gas producer having an annular grate frame, an upper series of grate bars extending across the same and bearing thereon and a lower series of grate bars in staggered relation to the upper series and suspended from said grate frame, and a supporting beam extending under the first series of grate bars and also suspended from the grate frame.
11. A gas producer having a grate frame, a series of grate bars arranged side by side and spaced from each other, means for mounting them on the frame, a second series of grate bars arranged below the first and opposite the said spaces between them, whereby the ashes fall through the said spaces and lie on the second series of grate bars at the angle of repose and means for adjustably hanging the second series of grate bars from the grate frame so that they may be moved toward and from the first, for the purpose specified.
15. 12. In a furnace, superposed series of grate members, the lower members having substantially horizontal upper faces and being spaced from each other to permit the discharge of ash or other residue between them and the upper members being arranged in vertical alinement with the spaces between the lower members, said upper members having inclined upper faces to direct material on to the substantially horizontal faces of the members of the lower series.
13. A grate structure formed of superposed series of members, all of said members being spaced from each other to permit the discharge of material between them, the lower members being disposed in vertical alinement with the spaces between the upper members, and said lower members having substantially flat upper faces to permit the banking of material thereon.
18. 14. In a grate structure, superposed series of fuel supporting members, all of the members being spaced apart to permit the discharge of material between them, the upper faces of the upper members being inclined to permit the ready discharge of material therefrom, and the upper faces of the lower members being substantially flat to receive said discharged material, said lower members being disposed substantially in vertical alinement with the space between the upper members.
15. In a grate structure, upper and lower series of spaced grate members, said upper members having inclined faces for directing material into the spaces therebetween, the members of the lower series being spaced from each other to permit the discharge of ash or other residue between them, said lower members being of greater width than the spaces between the upper members and arranged to receive and support all material discharge between said upper members.
16. The combination with a furnace; of upper and lower series of similar grate members, the members of the upper series having their lower faces in the same horizontal plane the members of the lower series being disposed below and wider than the spaces between the upper members and having flat upper faces in the same horizontal plane, the members of the lower series being spaced from each other to permit the discharge of ash or other residue between them.
17. In a furnace, a plurality of upper grate bars separated from each other to permit the discharge of material therebetween, a lower series of bars parallel with said upper bars and disposed below the spaces between the upper bars, said upper bars constituting means for feeding fuel on to the lower bars, and said lower bars being of a width determined by the angle of pile of the fuel, such width being sufficient to prevent the direct passage of fuel over the edges of said bars by gravity.
18. The combination with a furnace; of a lower series of spaced grate members therein having horizontal top faces and each shaped to support banked material and a series of upper grate members lapping and disposed to direct material onto the lower members, the space between the upper grate members being of such width as to prevent the feeding of material beyond the angle of pile of a bank which may rest upon the lower grate members.

In testimony whereof I have signed my name to this specification in the presence of two subscribing witnesses.

GODFREY M. S. TAIT.
